UNITED STATES PATENT OFFICE

RUDOLPH SAMUELS, OF CHICAGO, ILLINOIS, ASSIGNOR TO LUCIEN LELONG, INC., OF CHICAGO, ILLINOIS, A CORPORATION OF ILLINOIS

DESIGN FOR A BOTTLE OR SIMILAR ARTICLE

Application filed September 30, 1931. Serial No. 41,266. Term of patent 7 years.

To all whom it may concern:

Be it known that I, RUDOLPH SAMUELS, a citizen of the United States, and a resident of the city of Chicago, in the county of Cook and State of Illinois, have invented a new, original, and ornamental Design for a Bottle or Similar Article, of which the following is a specification, reference being had to the accompanying drawings, forming a part hereof.

On the drawings:

Figure 1 is a side elevation of a bottle or similar article, showing my new design, all four sides being the same as that shown.

I claim:

The ornamental design for a bottle, or a similar article, as shown and described.

RUDOLPH SAMUELS.
